UNITED STATES PATENT OFFICE

OTTO ROSTOCK AND JÜRGEN CLAUSSEN, OF ELMSHORN, GERMANY

DEVICE FOR CLEANING MATRICES

Application filed December 5, 1928, Serial No. 323,956, and in Germany January 7, 1928.

This invention relates to machines for cleaning matrices in which fresh benzine is continually conducted to the cleaning brushes or the like and the matrices are cleaned on 5 all sides. Devices of this character are already well known but certain disadvantages are existent therein, namely, the inability to rearrange the matrices in proper order as they leave the machine, and the matrices are 10 not acted upon with sufficient delicacy to avoid damage thereto.

The object of the present invention is to provide a particularly simple method and machine for cleaning matrices wherein the 15 above objections are overcome. For this purpose the matrices are first cleaned by means of brushes at the edge, at the foot and at the toothed portion in piles in a horizontal passage capable of being drawn inwardly, 20 and at the same time the grease is dissolved from the wide sides thereof. Thereupon the matrices are conducted separately by means of a matrix lifting device past brushes arranged at right angles to the feeding passage 25 and through a drying device whereby the wide sides and the lugs are cleaned and the matrices dried. The matrices are then conducted by travelling felt bands to a removable collecting device in which they are again 30 arranged in the form of a pile by means of inclined guide rails.

This method enables the matrices to be cleaned and dried efficiently on all six sides in one operation and by reason of the simple 35 construction an operation is obtained free from disturbance and as the machine is cheap in production the owners of the smallest composing machines are in a position to utilize the advantages of the invention.

40 In the accompanying drawings there is illustrated one example of construction of the machine.

Figure 1 is a partial sectional elevation of the machine with the matrix lifting device 45 in the lowermost position.

Figure 2 is an elevation with the matrix lifting device in the highest position.

Figure 3 is a section of the feed passage.

Figure 4 is a side elevation of the slide.

50 Figure 5 is an enlarged sectional view of

the collecting device with its supply device.

Figure 6 shows the matrix lifting device on a larger scale.

Figure 7 shows the position of a matrix 55 sliding on guide rails.

Figures 8 and 9 show a cleaning device on a larger scale.

The machine consists of a shallow casing divided into a number of compartments and having a front wall 1 (Figure 4), and a rear wall 2. The front and rear walls together with a matrix slide 3 form the feed passage. The matrix slide 3 is capable of being drawn rearwardly by means of its long shaft 4 and a hand piece 5 and can be retained in its outermost position by a locking lever 6. When the matrix slider 3 is drawn rearwardly a spring 7 is tensioned.

In an extension of the feed passage there are provided four brushes 8, 9, 10 and 11, 70 which, as shown in Figure 3, are made to conform with the shape of the matrices. In front of the brushes 8, 9, 10 and 11 there is also provided an adjustable controlling pin 12 which can be adjusted to suit various types of matrices to be cleaned. The movement of the matrices in the extension of the feed passage is limited by the partition wall 13. From here there extends at right angles to the feed passage a cleaning passage 14 formed by elements hereinafter described. The passage of the separate matrices through the cleaning passage 14 is effected by means of the matrix lifting device 15 which is guided in the lower portion of the cleaning passage by a guide member 16 and is connected by a crank rod 17 to a crank 18. Shoulders 19 are arranged on the member 15 for the purpose of lifting the matrices. Owing to the fact that the 80 matrices differ considerably from each other in thickness, the member 15 must be wider than the thinnest matrix. If then by chance two very thin matrices are arranged adjacent to each other, the member 15 must be prevented from lifting two or more matrices 85 at the same time, which is done by means of the shoulders 19. These shoulders must have a thickness equal to that of the thinnest matrix. Owing to the fact that the thickness 90 matrices have a width equal to that of the 95

100

thinnest matrix at the bottom, only one matrix at a time will be lifted by means of the shoulders 19 connected with the lifting device 15. In the path of the cleaning passage 14 there is also provided an abutment 20 for the purpose of preventing a second matrix sticking to the one which has to be lifted from being raised up by it.

The cleaning passage 14 has the upper portion thereof formed by brushes 22 and 23 which are resiliently and adjustably mounted in brush casings 21 and a cleaning device 24 comprising thin plates cut out of rubber or other material, these plates being arranged 15 one on top of the other and provided with tongue-shaped projections at their front surfaces. When the matrices pass between the two members forming the cleaning device 24 any dirt mixed with benzine and clinging to 20 the matrices is brushed off and flows downward out of the machine together with the benzine. The device 24 operates in a way which is similar to that of street cleaning machines wherein rubber plates are pushed 25 over the pavement and brush off the dirt and water. Above the cleaning passage 14 are provided two co-operating endless felt bands 25 and 26 which pass around rollers 27, 28, 29, 30, 31 and 32.

30 Of these rollers the roller 27 is driven directly by the crank 18 and produces the movement of the felt bands 25 and 26. At the point at which the bands 25 and 26, which run together over a portion of the periphery 35 of the roller 32, again separate, there is arranged the collector 33. The collector 33 consists of an inclined passage having guide rails 34 provided at the side walls thereof. In the discharge direction of the matrices 40 from the felt bands 25 and 26 there is provided a stop 35 which limits the movement of the matrices. At the lower end of the collector 33 there is provided a matrix receiver in the form of an angle iron 37, capable of 45 being withdrawn and into which the matrices slide as it is withdrawn, said receiver being preferably provided with a handle 36.

The roller 29 can be adjusted in position by means of the screw 38 so as to enable the 50 felt band 25 to be tensioned. Underneath the stripping device 24 openings 39 are provided in the rear wall 2 of the casing which serve for the supply of benzine from a benzine tank mounted on the machine or in any other suitable position. From these openings clean benzine flows in an uninterrupted course 55 through the brushes 22 and 23 and also through holes 40 to the brushes 8, 9, 10 and 11. The used benzine with the dissolved grease 60 from the matrices flows through a channel 41 into a gutter 42 and from here through an outflow passage 43 into a collecting tank, not shown.

The method of operation is as follows:—
65 The matrices 44 to be cleaned are, as will

be seen in Figure 1, placed in a stack in front of the matrix slide 3 when the latter is drawn rearwardly in the feed passage. The locking lever 6 is then released and the matrices are pushed along the feed passage by the pull exerted by the spring 7 on the slide 3, the pin 12 serving to indicate whether matrices of another type have been placed into the pile. When passing the brushes 8, 9, 10 and 11 which are sprayed with benzine the matrices are cleaned at the edges, at the foot and at the toothed portion thereof and the grease is somewhat softened on the wide sides and at the lugs. As soon as the first matrix 44 has reached the wall 13 the crank 18, which is in its lowermost position, is rotated and the matrix lifting device 15 is raised so that the first matrix is also raised. When passing between the brushes 22 and 23 supplied with benzine the matrix is cleaned on its wide sides and also the lugs thereof. On passing through the stripping device 24 any cleaning material still adhering to the matrix is removed.

In the meantime the crank 18 has completed half a revolution and has reached its highermost position. This position is illustrated in Figure 2. As will be clearly seen in this figure the matrix has already been gripped between the felt bands passing between the rollers 27 and 28 and on the further rotation of the crank 18 will be moved further between the bands and dried. The matrix lifting device 15 returns to its lowermost position so as subsequently to raise a further matrix which is operated upon in the manner just described.

When leaving the felt bands 25 and 26 the matrices reach an inclined surface on which they slide with their head foremost as far as the stop 35. When meeting the stop 35 the matrices turn about their horizontal axes as indicated in Figure 5 by reason of the fact that the lugs provided at the foot of the matrices are guided downwardly along a curve in grooves formed between the guide rails 34 and the bottom of the collector 33. As soon as the matrix is vertical the lugs provided at the head of the matrix slide on the guide rails 34 and the matrix now slides downwardly on the guide rails 34. When all the matrices of a pile have passed through the machine the slide 37 is withdrawn and the matrices which have passed into this can be removed in the form of a pile in exactly the same manner as they were passed into the machine.

We claim:—

1. A machine for cleaning matrices comprising a casing having a cleaning passage, a feed member in said casing movable transverse to said passage to feed matrices to one end thereof, brushes between which said matrices are passed as they are moved toward said passage, brushes in said passage, means

to adjust the latter brushes toward and away from each other, a cleaning device at one end of said passage, said device comprising a plurality of rubber members brushing over the 5 matrices passing through said device after engagement by said other brushes, drying means for the matrices, and a collector into which the dried matrices are discharged.

2. A machine for cleaning matrices, comprising in combination, a casing having a 10 horizontal cleaning passage, a feed member in said casing movable in said passage to feed matrices to one end thereof, brushes in said passage for cleaning the three narrow surfaces of said matrices as they are moved within 15 said passage, said casing comprising a second vertical cleaning passage situated at right angles to the first-mentioned passage, brushes in the second-mentioned passage, a 20 reciprocatory device movable in a plane at right angles to the direction of movement of said feed member, said device comprising a shoulder engaging a single matrix upon each reciprocation of said device and forcing said 25 matrix with its wide surfaces between the last-mentioned brushes in the second-mentioned passage, drying means to which each matrix is fed by said reciprocatory device, means situated between said brushes and said 30 drying means for supplying a washing liquid, and a collector into which the dried matrices are discharged from said drying means.

3. A machine for cleaning matrices, comprising in combination, a casing having a 35 horizontal cleaning passage, a feed member in said casing movable in said passage to feed matrices to one end thereof, brushes in said passage for cleaning the three narrow surfaces of said matrices as they are moved within 40 said passage, said casing comprising a second vertical cleaning passage situated at right angles to the first-mentioned passage, brushes in the second-mentioned passage, a reciprocatory device movable in a plane at 45 right angles to the direction of movement of said feed member, said device comprising a shoulder engaging a single matrix upon each reciprocation of said device and forcing said matrix with its wide surfaces between the 50 last-mentioned brushes in the second-mentioned passage, drying means to which each matrix is fed by said reciprocatory device, means situated between said brushes and said 55 drying means for supplying a washing liquid, and a collector into which the dried matrices are discharged from said drying means, said collector comprising a channelled member and guide rails mounted in the side walls of said channelled member and having curved 60 ends adjacent said drying means.

In testimony whereof we have affixed our signatures.

OTTO ROSTOCK.
JÜRGEN CLAUSSEN.
